UNITED STATES PATENT OFFICE.

EDWIN CHARLES ROWDON, OF SOUND BEACH, CONNECTICUT.

GOLD WASHING AND SAVING APPARATUS.

Application filed July 27, 1921. Serial No. 487,981.

To all whom it may concern:

Be it known that I, EDWIN CHARLES ROWDON, a citizen of the United States, residing at Sound Beach, in the county of Fairfield 5 and State of Connecticut, have invented a certain new and useful Improvement in Gold Washing and Saving Apparatus, of which the following is a specification.

My invention relates to that class of devices which are designed to be used in connection with dredges, such as are employed for example, along the course of the Snake River. It is well known that there have been numerous process machines and dredge 15 apparatuses which have endeavored to save the fine or flour gold, but they have not been successful. In fact, this is so well recognized that in Bulletin 620 issued by the United States Geological Survey, the statement is made (p. 294):

"The problem of saving the fine gold is one which has received much attention. None of the methods so far tried has proved entirely efficient or commercially successful."

My invention has for its object to provide a device which will recover from 10% to 25 30% more of the fine gold than can be recovered by any of the present processes, and to provide means for carrying out my process which are so simple as to make it commercially successful.

I have demonstrated in actual test that I recover 66% of the gold which escapes in the ordinary process. I am aware of the 35 fact that certain attempts have been made to save the fine gold by the employment of an elaborate system of sluices. These are exceedingly expensive and prevent the commercial success of the device. Other devices employ, in connection with the sluices, special riffles which are designed to save the coarser particles of gold. In the process employed by me, I entirely eliminate these expensive parts and accomplish a superior 40 45 result in the saving of flour gold.

My means of accomplishing the foregoing objects may be more readily understood by having reference to the accompanying drawing which is hereunto annexed and is a part 50 of this specification, in which

Fig. 1 is a side view partially in section,

showing means for carrying out my improved process.

Fig. 2 is a view taken on the line 2—2 in Fig. 1.

Similar reference numerals refer to similar parts throughout the entire description.

The drawings are more or less diagrammatic, being employed for the purpose of disclosing operative means for carrying out my invention without any reference to the specific details of construction which should be employed in the installation of a plant embodying my process, and I do not desire to be understood as limiting myself to the structure shown and described, for I believe that the hereinafter contained disclosure will be ample to enable persons skilled in the art to employ the invention irrespective of the specific structure illustrated in the drawings.

As shown in the drawings, the material coming from the dredge is deposited in a hopper 1 and is subjected to a stream of water from a pipe 2. The material passes through the hopper 1 on to a grizzly 3 which is inclined from the horizontal and may be supported in any suitable or desired manner.

As will be apparent from the drawings, the material from the dredge going through the hopper lands on the upper end of the grizzly screen and the smaller particles and values are washed down through the screen while the coarser material is rolled off on a chute to the waste pit 4. The finer materials are carried through a hopper 5 to a revolving trommel screen 6. This screen is preferably of $\frac{1}{4}$ " mesh which serves to screen out all material which is larger than that size. This material is carried out to an inclined chute 7 which conveys this material to the waste pit 4. The material which is small enough to pass through the mesh of the screen 6 enters with the water into a launder 8, the bottom of which is inclined so as to convey the material and water to a second trommel screen 9, the wire of which is preferably of #8 mesh.

In this screen the material which is too coarse to pass through the mesh is discharged on to a chute 10 which carries the coarser material to the waste pit 4. Again the fine material and the water pass into a

- launder 11 whence it is conveyed to a third trommel screen 12 which is of #30 mesh. This again separates the coarser material which is discharged from the screen 12 on to 5 a chute 13 whence the coarser material passes to the waste pit 4, while the fine and the water pass into a launder 14 which delivers both the water and all of the fine material to the amalgamator (not shown).
- 10 The screen 12 may be driven by a shaft 15 mounted in bearings 16 and 17 which are carried by suitable supports as 18, the power being applied to the shaft 15 through the medium of a pulley 19 from any convenient 15 source of power (not shown). Provision is made for the rotation of the trommel screen 9 by means of a sprocket 20 carried by the shaft 15 and a chain 21 which extends to a sprocket 22 mounted upon a shaft 23. This 20 shaft 23 carries the screen 9 and causes its rotation, the shaft being mounted in bearings 24 and 25 which are carried by suitable supports 26.
- A similar arrangement for the rotation of 25 the screen 6 is employed, comprising a sprocket 27 and chain 28 which extends to a sprocket 29 mounted upon the shaft 30 which is carried in bearings 31 and 32, these bearings being mounted upon supports 33.
- 30 It will be apparent from the foregoing description and operation that I entirely eliminate all sluices or sluices having riffles or pockets in which the values are caught and held, to be later removed by lifting the 35 riffles out and cleaning them. I do away with the use of all percussion tables or jiggers of any kind, and further, I do not employ the water to wash away the coarser material.
- 40 In my process it is my object to save the water and all of the fine material since I depend entirely upon the screen to get rid of the coarser material, my reason for this being that the water carries a very large 45 amount of flour gold in suspension, and where the water is carried away, as in the sluices and other systems, a large percentage if not all, of the flour gold is lost; whereas

in my process almost all of this flour gold is recovered since the water holding it in suspension is delivered to an amalgamator.

Having described my invention what I regard as new and desire to secure by Letters Patent is:

1. The herein described process for saving 55 flour gold, which comprises depositing the gravel upon a grizzly, subjecting the material to water, diverting the coarse material in one direction, carrying the finer material and the water in another direction to a trommel screen which separates the coarser material and diverts it to the waste pit, delivering the finer material and the water to a launder which conveys it to a second trommel screen where it is again separated, the 60 coarser material being diverted to the waste pit while the water and the finer material is carried into a second launder, which conveys it to a third trommel screen which again separates the coarser material which is diverted to the waste pit, while the fine material and all of the water is delivered to a 65 launder which conveys it to an amalgamator.

2. The herein described process for saving 70 flour gold, which comprises depositing the gravel upon a grizzly, subjecting the material to water, diverting the coarse material in one direction, carrying the finer material and the water in another direction to a screen which separates the coarser material 75 and diverts it to the waste pit, delivering the finer material and the water to a launder which conveys it to a second screen where it is again separated, the coarser material being diverted to the waste pit while the water 80 and the finer material is carried into a second launder, which conveys it to a third screen which again separates the coarser material which is diverted to the waste pit, while the fine material and all of the water 85 is delivered to a launder which conveys it to an amalgamator.

In testimony whereof, I have signed the foregoing specification.

EDWIN CHARLES ROWDON.
